PORTABLE VACUUM CLEANER

Joseph F. Billmyre, Larchmont, N. Y., assignor
to Allen Billmyre Corporation, New York,
N. Y., a corporation of New York

Application April 6, 1937, Serial No. 135,216

5 Claims. (Cl. 183—37)

This invention relates to new and useful improvements in a portable vacuum cleaner.

The invention has for an object the construction of a portable vacuum cleaner which is characterized by a vacuum producer mounted in a particular manner upon a resilient member capable of absorbing vibrations normally produced during the operation of the vacuum producer.

Still further the invention proposes the addition of sound retarding material to the body of the vacuum cleaner to encase the vacuum producer and confine noises produced during the operation thereof.

A further object of the invention is to so arrange the parts of the vacuum producer that the air current thereof is utilized to cool portions thereof likely to become heated, as for example, the prime mover operating the vacuum producer.

As a further object the invention contemplates an arrangement which will permit a portion of the body of the cleaner to be removed to uncover and expose the vacuum producer to make it accessible for repair and other purposes.

As a further object of this invention it is proposed to arrange an inverted self-cleaning filter bag within the body of the cleaner and to support this filter bag immediately below the vacuum producer and upon the resilient member so that vibrations which are absorbed by the resilient member are partially or fully transmitted to vibrate the filter bag and so assist in cleaning the bag.

Furthermore, it is contemplated to arrange the filter bag with several folds which are supported in open condition by resilient elements capable of vibrating and arranged to receive some of the vibrations naturally produced by the vacuum producer and so further assist in cleaning the filter bag.

Another one of the objects of this invention resides in arranging a can beneath the filter bag, and a mechanism for self-aligning the can in proper position when it is engaged in place.

Still further the invention proposes the arrangement of an inverted frusto-conical U-shaped packing element supported on the body of the vacuum cleaner and cooperative with the top edge of the can when the can is engaged in position for sealing the can against dust discharged.

Still further the invention proposes a novel mechanism for the quick and convenient engagement of the can in position and its removal when desired.

Another object of the invention is the construction of a device as described which is simple

and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a portable vacuum cleaner constructed according to this invention.

Fig. 2 is a side elevational view of the cleaner.

Fig. 3 is a transverse vertical sectional view thereof.

The portable vacuum cleaner includes a cylindrical body 18 having a bottom can receiving section 18a, an intermediate separator section 18b, and a top vacuum producing section 18c. A means for removably supporting a can 11 is arranged within the bottom section, and furthermore is capable of automatically centering the can and sealing the can as will be hereinafter more fully described. An inverted self-cleaning filter bag 12 is mounted within the intermediate section 18b and is positioned above the can 11. An air inlet 13 for a standard hose or set of hoses and cleaning tools is arranged to connect with the space over the can 11 and beneath the filter bag. A resilient annular member 14 is disposed within the cylindrical body between the top section 18c and the intermediate section 18b and is arranged to resiliently support a vacuum producer 15 for drawing air from beneath said filter bag.

The top section 18c of the cylindrical body is formed with a central top opening 16 through which the exhaust of the vacuum producer passes. Immediately below this opening there is a baffle disc 17. This baffle disc is insulated with a sound retarding material lining 17a, such as felt material. This insulated baffle disc is mounted upon the top of the vacuum producer.

The vacuum producer 15 comprises an electric motor 15a which is supported upon a fan casing 15b. This fan casing houses a two-stage centrifugal fan 15c which is connected to and driven by the electric motor 15. The fan casing 15b is extended through the central opening of the annular resilient member 14 and is fixedly mounted thereon. The fan casing 15b is made of several sections secured together as a unit and has a bottom opening 18 constituting the inlet. From this opening the air is drawn in by the lowermost fan blade and forced over 7 yards along the

passage 19 to an opening 20 which communicates with the passage 21 constituting the second stage chamber of the fan. The air then continues through the opening 22 to a compartment 23 located beneath the top wall of the fan casing 15b. From this compartment some of the air is forced through the motor 15a and discharges through openings 24 at the top of the motor. Other portions of the air are forced through openings 25 in the fan casing 15 and enters the space 26. The air from the openings 24 also enters the space 26 and from this space the air continues outwards around the baffle disc 17 and finally discharges from the top opening 16.

15 The top section 10c is lined with sound retarding material 27 such as felt material which acts to confine the noise produced by the electric motor 15a and the fan 15c. A switch 28 for controlling the motor 15a is mounted through the 20 wall of the top section 10c. A socket 29 for receiving an electric plug is also mounted upon the top section 10c. The switch and plug are connected in an electric circuit, not shown on the drawings, for controlling the electric motor. The 25 details of this circuit form no part of the invention and will not be described in this specification since circuits of this type are generally known.

The top section 10c is mounted on a bottom flange member 30 which extends over the intermediate section 10b. The upper end of the intermediate body section 10c is formed with a curled edge portion 31 disposed within the flange member 30. An annular support element 32 is attached to the upper portion of the intermediate 35 body section 10b. A plurality of studs 33 are mounted through this support element and extend through the annular resilient member 14 and through the top portion of the flange member 30. This top portion is formed with an annular recess 34 into which the edge of the top body section 10c engages. A clip 35 is mounted on each of the screws 33 and is clamped down by nuts 36 threadedly engaging the screws 33. These clips 35 are adapted to hold the top body 40 section 10c in position. When the nuts 36 are loosened the clips 35 may be turned around off the bottom edge of the top body section 10c which 45 may then be removed.

A screen 37 is supported upon the bottom end 50 of the fan casing 15b. This screen is arranged above the central filter portion of the bag 12. The filter bag 12 is formed from several adjacent wall sections connected together. There is an outer annular wall section 12a which is secured at 55 its bottom end to the lower edge of an annular wall 38 arranged concentric with the central body section 10b and supported upon the top support element 32. This wall 38 is sufficiently spaced from the inner section of the body section 10b 60 to form a passage 39 between these parts.

The upper edge of the filter bag wall 12a connects with the upper edge of another wall 12b. This wall 12b extends downwards and at its lower 65 end connects with the lower end of a cylindrical central portion 12c. The upper junction of the walls 12a and 12b are supported by several springs 40 which in turn are supported by an annular support element 41 resting on the support element 32 and fixedly held in position by the bolts 60 70 75 33. The support element 41 partially supports the resilient annular member 14 which is of a larger diameter than this element so that there is a free central projecting portion 14a of the resilient member 14. This free portion is capable of

vibrating and so absorbing the vibrations produced by the vacuum producer 15.

The lower edges of the walls 12a and 12b are connected at several points by springs 42. These springs are capable of vibrating and transferring some of the vibrations from certain portions of the filter bag to other portions to assist in cleaning the filter bag. The inlet 13 comprises a standard nozzle or union element upon which a rubber hose may be forced. This inlet 13 discharges into the annular space 39. From this annular space the air must travel downwards into the can 11 and then upwards and through the filter bag 12.

A frusto-conical wall element 44 is attached to 15 the lower portion of the intermediate body section 10b. An inverted frusto-conical V-shaped packing element 45 is mounted upon the outer face of the wall 44 and is adapted to engage over the top edge of the can 11 to shield the top of the can. 20 The can 11 is supported upon a bracket 46 which is located at the center of the can at the bottom. This bracket 46 is pivotally mounted on an arm 47 which is pivotally supported by a pin 48 intermediate of its ends. This pin 48 is supported on a bracket 49 mounted on the wall of a base element 50 secured upon the lower end of the bottom body section 10a. The arm 47 extends radially of the cylinder body, as clearly shown in Fig. 1, and has a projecting end 47a which acts as a treadle 30 upon which one may step.

The arm 47 is slightly loose on the pintle 48 so that it may pivot laterally a small amount. In one position it is disposed beneath a skirt portion of the base element 50 and in this position it 35 holds the can 11 raised. The treadle 47a may be pushed slightly laterally against a stop 51 (see Fig. 2) and then it is in line with a cut 53 formed in the skirt portion of the base element 50. When the treadle is now released it will be moved 40 upwards into the slot due to the weight of the can 11 on the bracket 46 which will be forced downwards. The top edge of the can in the lowered position will be free from the packing element 45 and then the can may be removed. The bottom body section 10a has an open side through 45 which the can may be removed. The can 11 is provided with handles 54 for convenience in handling it.

The base element 50 also supports a transverse 50 shaft 55 upon the ends of which there are casters 56. A bracket 51 is mounted upon the lower portion of the body section 10a and supports a third 55 caster 58. This third caster is located directly beneath the inlet 13. This third caster is of the swivel type so that it may turn around in all directions. The casters 56 are spaced on the other side of the center of the cylindrical body to that of the location of the caster 58. Upon diametrically opposite sides of the cylindrical 60 body 10 there are handles 60 by which the portable cleaner may be readily carried.

The operation of the device is as follows:

A hose and cleaning tools are attached to the inlet 13. The motor 15 is then turned on. The 65 fans 15c will draw in air from beneath it. This air must come from the inlet 13. The air from the inlet will first travel in the chamber 39 and then into the can 11, and travel upwards through the filter bag 12 and be drawn into the fan and 70 pass through and around the fan and finally discharge from the opening 16. Dust and other particles in the air will be caught by the filter bag and will fall down and settle within the can 11.

An important feature of the invention resides in the fact that the can 11 may be quickly and conveniently engaged into operative position and removed from position when it is required to be emptied. Merely by operating the treadle 41a it is possible to pivot the arm 47 to raise or lower the bracket 46. When the bracket 46 is raised the upper edge of the can will strike the inverted frusto-conical V-shaped packing element 45 and so automatically assume an aligned position on the packing element to seal the can from the outer atmosphere.

Another feature of the invention resides in the fact that the vacuum producer 15 is supported upon the resilient element 14. The advantage of this construction is that the vibrations produced by the vacuum producer 15 will not be transmitted to the cylindrical body, but will be confined and absorbed by the resilient annular member 14. A further feature resides in the fact that vibrations from the annular member 14 are utilized to vibrate the springs 40 which in turn will vibrate the filter bag and help in automatically cleaning the filter bag. Some of the vibrations in the filter bag will be transmitted by the stretched wall portions 12a and 12b to the springs 42 which will set up a vibration and further assist in cleaning the bag. Another feature of the invention resides in the fact that the central cylindrical portion 12c of the filter bag is loose, and when the vacuum cleaner is not working will fall downwards to the position 12cc indicated by the dot and dash lines, and when the vacuum cleaner is working will be inflated and will be vibrated and so shake the filter bag to cause it to drop accumulations of dust deposited on it.

Another important feature of the invention resides in the sound insulation applied to the disc 17 and to the top section 10c of the cylindrical body which will confine noise made by the vacuum producer 15 during its operation. A still further feature resides in the arrangement which permits the clips 35 to be disengaged from the lower edge of the top body section 10c which then may be readily removed to give access to the motor and fan.

While I have illustrated and described my invention with some degree of particularity, I realize that in practice various alterations therein may be made. For example, many of the features may be applied to a stationary vacuum system and other changes may be made. I therefore reserve the right and privilege of changing the form of the details of construction or otherwise altering the arrangement of the correlated parts without departing from the spirit or the scope of the appended claims.

Having thus described my invention, what I claim as new and desire to secure by United States Letters Patent is:

1. In a vacuum cleaner system, a cylindrical body, an inverted self-cleaning filter bag mounted within said body, an inverted frusto-conical wall supporting a V-shaped packing element and said wall being mounted on said body and around the bottom edge of said filter bag, a can within said body the top edge of which is adapted to engage said packing element when the can is lifted, and means for lifting said can.
2. In a vacuum cleaner system, a cylindrical

body, an inverted self-cleaning filter bag mounted within said body, an inverted frusto-conical wall supporting a V-shaped packing element and said wall being mounted on said body and around the bottom edge of said filter bag, a can within said body the top edge of which is adapted to engage said packing element when the can is lifted, and means for lifting said can, comprising a pivoted arm, a bracket on the inner end of the arm adapted to engage the bottom of the can at its center, and a base element mounted upon the bottom of said cylindrical body and having a skirt portion adapted to be engaged by the outer end of said arm to hold the arm pivoted so that the can is raised, said skirt portion being formed with a slot, and said arm being movable to a position to engage in said slot so that the arm may then pivot and the can be lowered.

3. In a vacuum cleaner system, a cylindrical body, an inverted self-cleaning filter bag mounted within said body, an inverted frusto-conical wall supporting a V-shaped packing element and said wall being mounted on said body and around the bottom edge of said filter bag, a can within said body the top edge of which is adapted to engage said packing element when the can is lifted, and means for lifting said can, comprising a pivoted arm, a bracket on the inner end of the arm adapted to engage the bottom of the can at its center, and a base element mounted upon the bottom of said cylindrical body and having a skirt portion adapted to be engaged by the outer end of said arm to hold the arm pivoted so that the can is raised, said skirt portion being formed with a slot, and said arm being movable to a position to engage in said slot so that the arm may then pivot and the can be lowered.

4. In a vacuum cleaner system, a hollow cylindrical body having a side opening through which a can may be placed therein, a bracket within said body and below said side opening for supporting said can, a vacuum producing device and filter bag mounted within said body above said opening, an annular member mounted on the internal face of said body above said opening, and means for slightly lifting said bracket for holding a can placed in said body through said opening against said annular member.

5. In a vacuum cleaner system, a hollow cylindrical body having a side opening through which a can may be placed therein, a vacuum producing device and filter bag mounted within said body above said opening, an annular member mounted on the internal face of said body above said opening, and means for slightly lifting and holding a can placed in said body through said opening against said annular member for firmly supporting said can beneath said vacuum producer and filter bag, comprising a support bracket adapted to engage the bottom of the can and means for holding said bracket in a raised position, including a pivotally supported lever connected at one end with said bracket, and a member engaging said lever to hold it in a position so that said bracket is raised, said latter member being formed with a cut into which said lever may be shifted so that the lever is free to pivot and lower said bracket.

JOSEPH F. BILLMYRE.
